DOOR LOCK

James Woodcock, 105 Chestnut Drive,
East Greenwich, R.I. 02818

Filed May 6, 1968, Ser. No. 11,788

Term of patent 14 years

Int. Cl. D8—03

U.S. Cl. D8—109

FIG. 1

FIG. 2

FIG. 3

FIG. 4

FIG. 5

FIG. 1 is a perspective view of a door lock showing my new design, the broken lines being for purposes of illustration;

FIG. 2 is a top plan view thereof;

FIG. 3 is an end elevational view looking from the right with respect to FIG. 1;

FIG. 4 is an end elevational view looking from the left with respect to FIG. 1; and

FIG. 5 is a rear elevational view thereof.

I claim:

The ornamental design for a door lock, substantially as shown and described.
